CLAIM

The ornamental design for a pentagon handle for a fishing rod, as shown and described.

DESCRIPTION

FIG. 1 is a perspective view of the fishing rod handle of the present invention;

FIG. 2 is an enlarged perspective view of the fishing rod handle of the present invention; and,

FIG. 3 is an end view of the fishing rod handle, with the opposite end being a mirror image thereof.

The broken line showing of a portion of a fishing rod is included for the purpose of illustrating only and forms no part of the claimed design.
